[57] CLAIM

The ornamental design for a directional compass for mounting on a surface, as shown.

DESCRIPTION

FIG. 1 is a perspective view of a compass for mounting on a surface showing my new design;

FIG. 2 is a left-side elevational view, the right side elevational view being a mirror image;

FIG. 3 is a top plan view;

FIG. 4 is a front elevational view; and,

FIG. 5 is a rear elevational view thereof.

The broken line showing of the compasses face, the indicia and the bracket are for illustrative purposes only and forms no part of the claimed design.

Fig. 1.
